ATTORNEY

UNITED STATES PATENT OFFICE.

FREDERICK WILLIAM EHRSAM, OF NEW YORK, N. Y.

ROTARY FAN.

SPECIFICATION forming part of Letters Patent No. 357,912, dated February 15, 1887.

Application filed October 21, 1885. Serial No. 180,470. (No model.)

To all whom it may concern:

Be it known that I, FREDERICK WILLIAM EHRSAM, a citizen of the United States, residing at New York, in the county of Westchester and State of New York, have invented new and useful Improvements in Rotary Fans, of which the following is a specification.

My invention relates to that class of rotary fans which are suspended from a bracket, as is used in offices, restaurants, &c., and which are preferably made loose on the driving-shaft, so that each can be put in motion or stopped independently of the motive power; and the object of my improvement is to effect this engaging and disengaging in a simple and efficient manner, as fully shown and illustrated in the accompanying drawings, in which—

Figure 1 shows the entire apparatus as attached to the ceiling. Fig. 2 shows an enlarged section of the disengaging apparatus out of gear, and in which the shaft revolves without the fan. Fig. 3 is a section similar to that of Fig. 2, but showing the position of the mechanism when the fan revolves with the shaft.

The same letters refer to the same parts in all the figures.

A in Fig. 1 is the bracket fastened to the ceiling, and having arms B and C, through which the driving-shaft E passes.

D is the driving-pulley, secured to the shaft E with key, set-screw, or pin, its boss just fitting between the arms B and C, and thus keeping the shaft in its position.

F is the fan-sleeve, fitting loosely on the shaft E, and having two bosses, G and G', to receive the arms H and H' of the fans, which are secured in their places with set-screws.

J and J' are collars pinned to the shaft E, one above and one below the fan-sleeve F, which is held in its place between them, but is free to revolve with the shaft or not, as the case may be.

The fan-sleeve F is provided with a vertical recess, K, upon its under side, and the collar J', with a vertical counterbored perforation, K' the counterbore being of the same size as the recess in the sleeve. A pin, P, is passed through the perforation, and has a head fitted

in the counterbore, which retains it in place, 50 and the lower end is secured in a cup-shaped sleeve, Q, which fits around the collar J', and has its upper portion preferably made flaring, as shown. By making the sleeve Q fit snugly around the collar the friction between the two 55 will hold the sleeve, and with it the pin, in place, even if the motive power should stop. By this construction the locking mechanism is entirely out of sight and the dust prevented from collecting in it, and the flaring mouth of 60 the sleeve will act as a drip-cup for the oil which is used to lubricate the fan-sleeve and shaft.

As the sleeve Q is constantly revolving with the shaft, and could not, therefore, be conveniently handled, it is provided with a loose wheel or ball, S, which is free to revolve on the rod R. The manner in which the mechanism is operated is now clear. The shaft E being constantly in rotation, the fans will 65 revolve with it or not, according as the sleeve Q is in the position shown in Fig. 3 or that of Fig. 2. Suppose the fans not to be in motion and it is desired to put them in gear. On laying hold of S and pushing it, and with it 70 the sleeve Q, up, as soon as in the course of a revolution the recess in the fan-sleeve comes into a position over the perforation in collar J the pin T will slip into the recess of the fan-sleeve and cause it to revolve with the collar 75 and the driving-shaft to which it is attached. The head of the pin P is made long enough to fit into both the recess and counterbore of the perforation, and the collar J above the fan-sleeve prevents the sleeve from being slipped 80 up the shaft when the pin is pushed up to lock the device ready for operation. To stop the fan it is only necessary to pull down S, and with it the sleeve Q and the pin P, into the position shown in Fig. 2.

Having fully described my invention, what I desire to claim and secure by Letters Patent is—

1. In a rotary fan, the combination of a vertical shaft, a collar secured to the lower 95 end of said shaft, having a vertical counterbored perforation, a fan-hub loosely journaled upon said shaft, having a recess in its lower

side, a pin in the perforation of said collar, having a head, said shaft, collar, hub, and pin being adapted to so engage and coact with each other as to prevent the accumulation of dust 5 within said recess or aperture.

2. In a rotary fan, the combination of a vertical shaft, a collar secured to its lower end, having a vertical counterbored perforation, a fan-hub loosely journaled upon said shaft, having a recess in its lower side, a pin in said perforation, having a head upon its upper end, and a flaring cup-shaped sleeve secured to

the lower end of said pin, said sleeve engaging with said collar and holding the pin in engagement with the hub by means of frictional contact with the collar. 15

In testimony that I claim the foregoing as my own I have hereunto affixed my signature in presence of two witnesses.

FREDERICK WILLIAM EHRSAM.
